JOHN C. BLEVNEY, OF NEWARK, NEW JERSEY.

GRINDING AND POLISHING MACHINE.

1,043,194.

Specification of Letters Patent.

Patented Nov. 5, 1912.

Application filed November 27, 1911. Serial No. 662,532.

To all whom it may concern:

Be it known that I, JOHN C. BLEVNEY, a citizen of the United States, residing at Newark, in the county of Essex and State 5 of New Jersey, have invented certain new and useful Improvements in Grinding and Polishing Machines; and I do hereby declare the following to be a full, clear, and exact description of the invention, such as 10 will enable others skilled in the art to which it appertains to make and use the same, reference being had to the accompanying drawings, and to characters of reference marked thereon, which form a part of this 15 specification.

This invention has reference, generally, to improvements in grinding and polishing machinery.

The present invention has for its principle 20 object to provide an efficient apparatus for grinding and polishing objects having two or more flat surfaces, such for example as square, or other polygonally-shaped rods or tubing; and, it is the purpose of the machine to provide such objects with a smooth, 25 uniform, and highly finished surface, free from blemishes, burns, or buckling appearance.

In addition to this object, the present invention provides a quick and efficient means 30 for handling and controlling the movements of the objects to be ground or polished, so that the same may be properly and completely treated by the grinding and polishing elements of the machine.

The various specific objects of the present invention, not at this time more particularly enumerated, will be clearly understood from the following detailed description of 35 this invention.

With the various objects of the present invention in view, the said invention consists, primarily, in the novel grinding and polishing machine hereinafter set forth; and, 40 the invention consists, furthermore, in the novel arrangements and combinations of the several devices and parts, as well as in the details of the construction of the same, all of which will be more fully described in the 45 following specification, and then finally em-

bodied in the clauses of the claims which are appended to and which form an essential part of the said specification.

The invention is clearly illustrated in the accompanying drawings, in which:—

Figures 1 and 2 are side elevations of the respective opposite sides of a grinding and polishing machine, showing one embodiment of the principles of the present invention; and Fig. 3 is a detail plan view of the work-supporting table and the automatic work-feeding and work-carrying mechanism connected therewith, said view being made on an enlarged scale. Fig. 4 is a detail cross-section, taken on line 4—4 in said Fig. 3, looking in the direction of the arrow α ; Fig. 5 is a detail side elevation and part longitudinal vertical section of a gravity presser-foot, made on an enlarged scale, and removed from its connection with the machine, the same being adapted to press the grinding element or belt against the material or objects to be worked upon; and Fig. 6 is a transverse vertical section of the same, said section being taken on line 6—6 in said Fig. 5. Fig. 7 is a large detail plan view of a portion of the feeding element or belt, showing in connection therewith, the means of attaching or connecting the objects to be polished or ground thereupon; Fig. 8 is a detail longitudinal vertical section of the same, taken on line 8—8 in said Fig. 7; and Fig. 9 is a detail vertical longitudinal section of a means for adjusting the tension of the feed-belt of the apparatus.

Similar characters of reference are employed in all of the above described views, to indicate corresponding parts.

Referring now to the said drawings, the reference-character 1 indicates the frame of the machine, and 2 indicates the main driving shaft which is suitably supported in bearings in the upper portion of said frame. Secured upon one end-portion of said shaft 2 is a pulley 3, over and around which passes a belt 4 for driving the machine, and suitably secured upon said driving shaft 2 is a driving-pulley 5. Extending from the upper portion of said frame 1 are oppositely directed arms 6 and 6^a in

which are respectively supported suitable adjustable bearing-brackets 7 and 7^a which carry the respective shafts 8 and 8^a upon which are rotatably mounted the pulley-wheels 9 and 9^a.

The reference-character 10 indicates a suitable cushion-belt which is provided upon its outer surface with suitably formed serrations, said belt passing around the said driving pulley 5 and said pulley-wheel 9. Extending around the said pulley-wheels 9 and 9^a, outside of the belt 10, is a grinding belt 11, the same being preferably made of a suitable fabric, such as cloth or webbing, the outer surface of which is covered with a suitable abrading or polishing material, such as emery, or the like. Extending outwardly from the lower portion of said frame 1 is an arm 12 which is internally screw-threaded adjacent to its free end, so as to thereby provide a bearing for a hollow screw-threaded standard 13, the lower end of which is provided with a suitable hand-wheel 14, for the proper manipulation of the same. The reference-character 15 indicates a suitable table-beam bracket having an offset-member 16 to which is secured a table-beam 17, in such a manner, so as to provide a free space beneath the latter. Extending downwardly from said bracket 15 is a cylindrical shank 15^a which is mounted so as to slide vertically within said hollow screw-threaded standard 13, and suitably secured upon said shank 15^a is a split collar 15^b, against which the upper face-end of said hollow screw-threaded standard 13 bears, so as to support said bracket 15 in such a manner, that it is capable of a slight vertical movement, limited, however, in its downward direction by the stop afforded by said hollow screw-threaded standard 13. The rough vertical adjustments of the supporting position of said table-beam-bracket 15 may be secured by moving the said split collar 15^b up or down upon said shank 15^a, and the finer adjustments may then be made by raising or lowering said hollow-screw-threaded standard 13, by turning the hand wheel 14. Said table-beam 17 is provided with transversely and horizontally extending supporting arms 18 which are formed with suitable bed-brackets 19, each bracket having a pair of downwardly extending portions 20, the free ends of which form bearings which are slidably connected or arranged upon the respective supporting arms 18. Suitably supported by means of said respective bed-brackets 19 is a longitudinally extending work-supporting table 21, which is arranged in such a manner, so that it extends beneath the said grinding belt 11, where the latter is presented in its grinding position. Secured at one end of said work-supporting table 21 is a bracket-member 22 which is provided with a pair of bearing-ports 23 in which is

journaled a driven shaft 24, upon which is suitably mounted a feed-belt pulley 25. Secured at the opposite end of said work-supporting table 21 is an adjustable bracket-member 26 which is also provided with bearing-ports 27 in which is mounted a shaft 28, said shaft 28 having mounted thereon an idler-pulley 29. The reference-character 30 indicates a feed-belt which passes around the said feed-belt pulley 25, and extends longitudinally above said table in alignment with said grinding belt 11 and beneath the same, and then passes over said idler-pulley 29 and returns beneath said work-supporting table, and table-beam, through the free space between the said table-beam 17 and said table-beam-bracket 15, the latter being provided with arms 15^c upon which are mounted anti-friction rollers 15^d upon which said returning portion of the feed-belt 30 rides. The purpose of mounting said bracket-member 26 adjustably in connection with said table 21 is to provide a means for carrying said idler-pulley 29 in a manner to permit of adjusting the tension of the said feed-belt 30. To this end, said adjustable bracket 26 is provided with a tail-piece 26^a which is slidably mounted so as to move inwardly or outwardly in a track-piece 26^b which is secured to the under surface of said table 21. Said tail-piece 26^a is provided upon its upper surface with a ratchet or a series of serrations 26^c, arranged so as to be engaged by a pivotally mounted pawl 26^d which is suitably connected with said track-piece 26^b. The pull of said feed-belt pulls said ratchet 26^c against said pawl, whereby said bracket-member is held in its adjusted position to produce the desired tension of said feed-belt 30, in a manner clearly to be understood from an inspection of Fig. 9 of the accompanying drawings. Said pawl 26^d may be provided with a finger-piece 26^e which may be manipulated through the opening 26 in the table 21 in which said pawl lies, so that the same may be quickly released from its holding engagement with said ratchet, to allow said bracket-member 26 to be moved inwardly to any desired position. The reference-character 31 indicates a pulley which is secured upon said main driving shaft 2 and over which runs a belt 32 for driving a larger pulley 33 which is secured upon a counter-shaft 34, and which shaft is journaled in suitable bearings in the lower portion of the frame 1. Suitably connected with said frame 1 is an outwardly extending arm 35 upon which is secured, in any desired position, and is capable of longitudinal adjustment thereon, a bearing-member 36 in which is adjustably journaled a counter-shaft 37, upon one end of which is fixed a pulley 38. Mounted upon the said counter-shaft 34 is a small pulley 39 over which runs a belt 40, by means of which the

said pulley 38 and counter-shaft 37 are driven.

The reference-character 41 indicates a transversely arranged shaft which is journaled in a bearing-member 42 connected with the previously mentioned table-beam, and 43 indicates a transmission shaft which operates between the said counter-shaft 37 and the said transverse shaft 41. Operatively connecting the said counter-shaft 37 with said transmission shaft 43 is an incased set of intermeshing bevel gears 44, the members of which are respectively connected with said counter-shaft 37 and said transmission shaft 43, whereby the movement or rotation of the former is transmitted to the latter. In like manner, operatively connecting said transmission shaft 43 with said transverse shaft 41 is an incased set of intermeshing bevel gears 45, the members of which are respectively connected with said transmission shaft 43 and said transverse shaft 41, whereby the movement or rotation of the former is, in turn, transmitted to the latter, all of which will be clearly evident from an inspection of the several figures of the drawings.

It is desirable that the work-supporting table 21 shall have a transverse reciprocatory movement during the operation of the machine, to the end, that the work to be ground or polished may be carried in contact transversely with all portions of the grinding belt 11, so that the entire grinding efficiency of the belt may be utilized, and the same prevented from streaking or wearing off in limited portions of its grinding surface, instead of being uniformly and evenly worn off. To accomplish this result, there is provided a longitudinally extending rock-shaft 46 which is supported by means of shaft-hangers 47, depending from portions of said supporting arms 18 of the table-beam 17. Secured in proper locations upon said rock-shaft 46 are suitable lever-arms 48, said lever-arms being pivotally connected with the bed-brackets 19, by means of connecting rods 49. Fixed upon said rock-shaft 46 is a rocker-arm 50 which is provided with an anti-friction roller 51, said roller being in operative engagement with the cam-surface 52 of a rotating cam-wheel 53, which is affixed to and is rotated by means of said transverse shaft 41. The rotation of the said cam-wheel 53 tends to reciprocate said rocker-arm 50, so as to oscillate the said rock-shaft 46 and lever-arms 48, and, the latter operating through said connecting rods 49, slide the said bed-brackets 19 back and forth upon said supporting arms 18, and consequently reciprocate the rock-supporting table 21 in transverse directions. Secured to said rock-shaft 46 is an outwardly extending arm 54 which is provided with a counter-balance or weight

55, which tends to maintain said rocker-arm 50 and its anti-friction roller 51 in constant engagement with the cam-surface 52 of said cam-wheel 53, by oscillating the rock-shaft in the opposite direction during the slackening movement of said cam-wheel, and thereby assists in producing the reciprocatory movements of said work-supporting table, as will be clearly understood. Connected with said transverse shaft 41 is a variable speed or step-pulley 56 over which runs a belt 57 which rotates another variable speed or step-pulley 58, said pulley 58 being fixed upon one end of a transverse counter-shaft 59 journaled beneath said work-supporting table 21. Connected with the opposite end of said transverse counter-shaft is a pulley-wheel 60 over which runs a belt 61 adapted for the purpose of driving another pulley wheel 62 which is secured to said driven shaft 24, and by means of which the latter is caused to rotate said feed-belt pulley 25 and thereby drive said feed-belt 30. The said work-supporting table 21 is provided with means for backing or supporting the said feed-belt 30 at the point where the same presents the objects carried thereby to the action of the grinding belt 11, so that said feed-belt is not permitted to yield under the pressure of said grinding-belt upon the objects to be ground or polished; but rather, said feed-belt is compelled to hold or press the said objects unresistingly against said grinding belt. This feed-belt backing or supporting means comprises a pair of base-plates 63, registering longitudinally beneath the marginal edges of said feed-belt, and supported upon said base-plates 63 are suitable side-flanges 64, the upper marginal edges of which are parallel to the feed-belt and extend slightly above the upper surface of said belt, said flanges providing suitable guides between which the said feed-belt runs. Longitudinally disposed between the said base-plates and their side-flanges are a plurality of backing-members 65, said members comprising longitudinal strips, the lower edges of which are supported upon said work-supporting table, and the upper edges of said strips being presented against the under side of said feed-belt in supporting or backing relation thereto. Said backing-members 65 are suitably spaced apart, to provide intervening spaces 66, suitably formed spreader-blocks 67 being intermediately disposed between said members 65. Said base-plates 63, side-flanges 64, backing-members 65, and their spreader-blocks 67, are all bound together, in their operative relation, by means of suitably constructed and transversely extending tie-bolts 68. The body of said feed-belt 30 is provided with a plurality of suitably disposed and staggered elongated openings or perforations 69, which are positioned in such a manner, that, as the

said feed-belt moves over the backing means, said openings or perforations will register over one or the other of said intervening spaces 66, whereby a holding member, which is used in connection with the work to be ground or polished and which is connected with said feed-belt, may not be interfered with by any contact with said backing means.

As heretofore stated, the machine embodying the principles of the present invention, is peculiarly adapted to grind and polish such objects, as lengths of square rods or tubing, or rods or tubing of rectangular or other polygonal cross-section. I have, therefore, represented a plurality of lengths of square tubing, indicated by the reference numeral 70, disposed upon said feed-belt 30, so as to be carried thereby beneath said grinding belt 11. Said grinding belt is arranged to run in such a manner, that its abrading surface travels in the same direction as the work carried by said feed-belt, but at a little faster speed. When the work, therefore, is carried in contact with the running abrading surface of the grinding belt, the contact is apt to cause the work to slip ahead upon said feed-belt, faster than said feed-belt is arranged to carry the same, and to the detriment of the proper action of the abrading surface upon the work. It is therefore necessary, to provide means to prevent the tubing 70 from slipping forward upon said feed-belt when submitted thereby to the action of said grinding-belt; and, for this purpose, the holding member hereinabove mentioned is provided. Said holding member comprises a loop-portion 71 which is adapted to extend into the forward open end of said tubing 70, and, extending downwardly from said loop-portion is a stop-piece 72 adapted to be inserted in one of said openings or perforations 69 of the feed belt, so as to be engaged by said feed-belt, and thus afford a stop for preventing the tubing from sliding forward upon said feed-belt, or moving faster than said feed-belt is arranged to carry the same. Connected with said loop-portion 71, and extending forwardly thereof, is a flat loop 73 which lies in the plane of said feed-belt, so as to rest upon the surface thereof in a manner adapted to prevent said tubing from tipping or otherwise slipping said stop-piece 72 out of its proper engagement with the perforation 69 of the feed-belt. The said stop-pieces 72 project beneath the under surface of the feed-belt, so as to be engaged by the surface of said idler-pulley 29 which, upon such contact, pushes said stop-pieces out of the perforations 69, and prevents the tubes from being tipped upwardly when the feed-belt travels around the idler-pulley, and whereby said tubing is released from any positive connection with the feed-belt and is free to be delivered therefrom to a receiv-

ing table, conveyer, or other means for receiving the finished tubing. Connected with the respective opposite ends of said work-supporting table 21 are counter-balancing mechanisms for maintaining the balance of the table in its horizontal plane, and a proper vertical play or movement of the same is permitted by the sliding connection of the shank 15^a with the herein-above screw-threaded standard 13. By such means, the work-supporting table and its feed-belt may be said to be "floating", so that, when uneven spots in the tubing are met with and as the same contact with said grinding belt 11, said table will yield sufficiently to prevent too much pressure of the abrading surface upon said tubing, thus preventing burns or blisters, and improperly ground or polished spots to appear upon the tubing. Such floating relation of the table and its feed-belt is particularly essential when grinding or polishing tubing covered with a veneer of thin metal, such as brass-veneered iron tubing which is used in manufacturing beds, and which it is desired to provide with a very highly polished finish. Each counter-balancing mechanism comprises a yoke-piece 74, connected at the under side of said work-supporting table, the same being curved around to provide a free space for the return-portion of said running feed-belt. Connected with the lower arm of said yoke-piece 74 is a downwardly depending link-piece 75 which is provided at its lower end with a hook-member 76 for pivotally engaging the eye of one end of a lever-arm 77, in such a manner, so as to allow not only the pivotal movement of said lever-arm 77, but also to allow a pivotal movement of said link-piece 75 at right angles thereto, which is made necessary by reason of the transverse reciprocation of said work-supporting table, as above described. Said lever-arm 77 is fulcrumed in a suitable bearing-standard 78. Secured upon the free end of said lever-arm 77 is a counter-balance or weight 79, the same being adjustable with relation to its distance from the fulcrum of said lever-arm, so that a proper degree of balancing force may be applied to properly support said table in its so-called "floating" condition.

The reference-character 80 indicates the supporting frame-work of a gravity presser-foot mechanism which is connected with the arm 6 of the machine-frame 1, so as to present said presser-foot mechanism above the said superimposed belts 10 and 11, at a point where the grinding belt comes in contact with the work to be ground. The object of said presser-foot is to yieldingly press said grinding belt against the work, and thus assure the efficient operation of the abrading surface thereof upon the work to be ground. Said presser-foot comprises a rec-

tangular frame 81 which is provided upon its longitudinal sides with a plurality of outwardly projecting studs 82, said studs riding in properly disposed slots 83, with which said frame-work 80 is provided. Pivotally connected with said rectangular frame 81, by means of their side-arms 84, are a plurality of transversely extending presser-weights 85, the same being provided at their upper outer ends with outwardly projecting lugs or studs 86, which engage the upper edges of the longitudinal side-pieces of said rectangular frame 81, and serve to limit the downward movements of said presser-weights 85. Said frame 81 is arranged and supported in such a manner, in its relation with the frame-work 80, that the same may be lifted to raise said presser-weights from their operative contact with the belts 10 and 11. To this end, there is provided a shaft 87, having eccentric or cam-shaped portions 88 which are journaled in a suitable manner in the upper portion of said frame-work 80, and connecting said shaft 87 with a pair of opposite studs 82 of said rectangular frame are a pair of supporting links 89. A handle-member 90 is secured to said shaft 87, by means of which the same may be rotated. Upon rotating said shaft 17, the eccentric or cam-shaped portions tend to raise the shaft, such upward movement being transmitted to said rectangular frame 81 by means of the said supporting links 89, said rectangular frame being guided in its vertical movements by the studs 82 which ride in the slots 83 of said frame-work 80, and said presser-weights being prevented from swinging out of said rectangular frame 81 when the same is so raised, by means of the engagement of the lugs or studs 86 coming in engagement with the latter. It will be apparent, that when said rectangular frame 81 is lowered to its operative position, the said presser-weights 85 are carried downwardly until their lower edges are brought in contact with said belts 10 and 11, and the same being each independently pivoted to said frame, they each extend transversely in engagement with said belts, and each exert, by reason of the gravitation of said weights, a yielding pressure upon all portions of the belts passing thereunder, so that said grinding belt is caused to bear properly and firmly upon the flat surfaces of the tubing 70 presented to the action of said grinding belt, as the same is carried forward into contact therewith by said feed-belt.

It will be understood, that veneered tubes, such as are used for bedsteads, comprise a tubular base upon which is imposed a very thin sheet of brass forming the veneer. In such tubes, irregular spots, higher than the general surface of the tube will appear, and if too much grinding pressure is brought to bear upon such spots or irregularities, blis-

ters will occur, or the veneer may be ruptured or broken through. For this reason, the machine must operate in such a manner that the pressure of the grinding belt is automatically regulated, so that it will bear uniformly upon all portions of the surface of the tube passing beneath the same. Such uniform pressure of the grinding belt is accomplished through the balanced "floating" arrangement of the work-supporting table 75 coöperating with the action of the gravity presser-foot upon the grinding belt, since, if an irregular or high spot in the tube is met with, the balanced table yields slightly, and the grinding belt is pressed downwardly by 80 the presser-weights of said gravity presser-foot, so that the grinding belt tends to follow their yielding movement. The tension, however, of the grinding-belt, which is driven at a fixed speed, tends to overcome 85 the downward pressure of said presser-weights, when the same seek to press the grinding belt too far out of its normal path of movement; hence, the excess of grinding pressure, such as would exist if the work 90 was not permitted to yield, as a high spot is presented, is obviated, and the grinding pressure is equalized instead.

It will be clearly evident, that the abrading surface of the grinding belt 11 can only act upon one side of the rectangular tubing 70; hence, the same must be passed beneath the said grinding belt as many times as it possesses sides or surfaces to be treated. In order to make the machine complete and to facilitate the handling of the tubing by the operator, means for quickly returning the partially ground or treated tubing to the point where the same may be again placed upon said feed-belt 30, is provided, 95 so as to again be carried beneath the grinding belt 11. This means comprises a return-conveyer mechanism consisting of a pair of side-frames 91, said frames having at their forward ends suitable bearing-portions 92 which are adapted to straddle one end of said driven shaft 24, in order to support the said side-frames 91 at one end. The opposite ends of said side-frames 91 are supported by the cross-bar 93 of the 100 yoke-piece 94 of a suitable standard 95. Connected with said driven shaft 24, so as to be rotated thereby, is a pulley wheel 96, and journaled in said side-frames 91, so as to extend transversely therebetween 110 and throughout their lengths, are a plurality of idler-rollers 97 over which runs a conveyer-belt 98. The pair of idler-rollers at the extreme forward ends of said side-frames are suitably spaced with reference to each other, so that they press the said conveyer-belt 98, as it runs over the same, against the upper side of said rotating pulley-wheel 96, thereby permitting the said pulley-wheel 96 to impart motion to 115 120 125 130

5 said conveyer-belt 98 in the direction opposite to the direction of movement of said feed-belt 20. The said idler-rollers support the carrying-portion of said conveyer-belt in a horizontal plane, and in a proper position to carry or convey the tubing placed thereon. As the tubing 70 passes away 10 from contact with said grinding-belt 11, it is removed from said feed-belt 30, and is then placed upon said conveyer-belt 98 which conveys the tubing back to the starting point, whereupon the operator takes the tubing and again places it upon the feed-belt 30, so that another side thereof 15 is presented to the action of the grinding belt. These operations are repeated until all sides of the tubing have been subjected to the action of the grinding belt.

20 The operation of the herein-above specified and novel construction of grinding and polishing machine, and its various parts, in the performance of its functions, will be readily understood from the foregoing specification, and an inspection of the accompanying drawings, without the necessity of further description.

25 As many changes may be made in the herein-above described construction of my invention and its detail parts, and many 30 apparently widely different embodiments of my invention could be made without departing from the scope thereof, I intend that all matter contained in the above description, or shown in the accompanying 35 drawings, shall be interpreted as illustrative and not in a limiting sense. I desire it also to be understood, that the language used in the following claims is intended to cover all generic and specific features of 40 the invention herein described, and all statements of the scope of the invention, which, as a matter of language, might be said to fall therebetween. Hence, I do not limit 45 my present invention to the exact arrangements and combinations of the devices and parts, as described in the said specification, nor do I confine myself to the exact details of the construction of the said parts, as illustrated in the accompanying 50 drawings.

I claim:—

1. In a device of the class described, an abrading means, a work-supporting table arranged beneath the same, a feed-belt 55 mounted in connection with said table for feeding the work to said abrading means, means for driving said feed-belt, means for automatically causing a transverse reciprocation of said table, and means for raising 60 and lowering said table.

2. In a device of the class described, an abrading means, a transversely reciprocating work-supporting table arranged beneath the same, means for supporting said 65 table so as to permit a slight vertical play

of the same, a feed-belt mounted in connection with said table for feeding the work to said abrading means; means for driving said feed-belt, and a counter-balancing mechanism connected with each end of said 70 table to balance the same in its vertical movements.

3. In a device of the class described, an abrading means, a work-supporting table arranged beneath the same, a feed-belt mounted 75 in connection with said table for feeding the work to said abrading means, means connected with said table for backing or supporting said feed-belt as it passes beneath said abrading means, and means for driving 80 said feed-belt.

4. In a device of the class described, an abrading means, a work-supporting table arranged beneath the same, a feed-belt mounted 85 in connection with said table for feeding the work to said abrading means, means for driving said feed-belt, a holding member adapted to be connected with said feed-belt, and a backing means provided with spaces 90 for the free passage of said holding member, said backing means being arranged upon said table so as to support said feed-belt as it passes beneath said abrading means.

5. In a device of the class described, an 95 abrading means, a work-supporting table arranged beneath the same, a feed-belt mounted in connection with said table for feeding the work to said abrading means, said feed-belt being provided with a plurality of perforations, a holding member adapted to engage 100 said feed-belt by insertion in one of said perforations, said holding member being adapted to engage the work to prevent the same from slipping forward upon said feed-belt when engaged by said abrading means, 105 and means for driving said feed-belt.

6. In a device of the class described, an abrading means, a work-supporting table arranged beneath the same, said table having 110 a balanced vertical movement, means for transversely reciprocating said work-supporting table, a feed-belt mounted in connection with said table for feeding the work to said abrading means, means connected 115 with said table for backing said feed-belt as it passes beneath said abrading means, a holding member adapted to engage both said feed-belt and the work to prevent the latter from slipping forward upon said feed-belt 120 when engaged by said abrading means, and means for driving said feed-belt.

7. In a device of the class described, an abrading means, a work-supporting table arranged beneath the same, said table having 125 a balanced vertical movement, means for transversely reciprocating said work-supporting table, a feed-belt mounted in connection with said table for feeding the work to said abrading means, means connected 130

- with said table for backing said feed-belt as it passes beneath said abrading means, a holding member adapted to engage both said feed-belt and the work to prevent the latter 5 from slipping forward upon said feed-belt when engaged by said abrading means, a gravity presser-foot engaging said abrading means to yieldingly press the same to the work, and means for driving said feed-belt.
8. In a device of the class described, an abrading means, a work-supporting table arranged beneath the same, a feed-belt mounted in connection with said table for feeding the work to said abrading means, means for 10 driving said feed-belt, a backing means connected with said table for supporting said feed-belt as it passes beneath said abrading means, comprising a plurality of longitudinally extending backing members arranged 15 to provide intervening spaces, and means for supporting said backing members, said feed-belt being provided with a plurality of perforations adapted to register above said intervening spaces of said backing means as 20 said feed-belt rides upon the same, and a work-holding member adapted to engage said feed-belt by insertion in one of said perforations.
9. In a machine of the class described, a 25 frame, a driving shaft, an abrading means driven thereby, a work-supporting table, having a balanced vertical movement, means connected with said frame for adjustably supporting said table with relation to said 30 abrading means, means for transversely reciprocating said table connected through intermediate mechanism to said driving-shaft, a feed-belt mounted in connection with said table, and means for driving said feed-belt 35 also connected through said intermediate mechanism to said driving shaft.
10. In a machine of the class described, a frame, a driving shaft, an abrading means driven thereby, a work-supporting table, 40 having a balanced vertical movement, means connected with said frame for adjustably supporting said table with relation to said abrading means, means for transversely reciprocating said table connected through intermediate mechanism to said driving shaft, a feed-belt mounted in connection with said table, means for backing or supporting said feed-belt as it passes beneath said abrading means, a gravity presser-foot carried by said 45 frame adapted to be brought into contact with said abrading means to hold the same yieldingly in contact with the work carried by said feed-belt, and means for driving said feed-belt also connected through said intermediate mechanism to said driving shaft.
11. In a machine of the class described, a frame, a driving shaft, an abrading means driven thereby, a work-supporting table beneath said abrading means, a bracket-mem- 50 ber at one end of said table, a driven shaft 65 journaled therein, a feed-belt pulley mounted on said driven shaft, another bracket-member at the opposite end of said table, a shaft carried thereby, an idler-pulley mounted on said shaft, a feed-belt running over said feed-belt pulley and said idler-pulley, means for adjusting said idler-pulley to tension said feed-belt, and intermediate transmission mechanism connecting said driven shaft with said driving shaft. 75
12. In a machine of the character described, an abrasive element, means for holding said abrasive element yieldingly to its work, comprising a frame-work, a plurality of transversely extending presser-weights, 80 means for pivotally connecting said presser-weights to said frame-work to permit in each of the same an independent vertical play, and means for raising and lowering said frame-work to carry said presser-weights away from or into operative contact with said abrasive element. 85
13. In a machine of the character described, an abrasive element, means for holding said abrasive element yieldingly to its work, comprising a frame-work, a plurality of transversely extending presser-weights, 90 means for pivotally connecting said presser-weights to said frame-work to permit in each of the same an independent vertical play, means for raising and lowering said frame-work to carry said presser-weights away from or into operative contact with said abrasive element, and means connected 95 with each presser-weight for engaging said frame-work to limit the downward swing of said presser-weights when said frame-work is raised away from said abrasive element. 100
14. In a machine of the class described, a frame, a hollow screw-threaded standard adjustable in a portion of said frame, a table-beam-bracket provided with a shank slidably disposed in said hollow screw-threaded standard, a table-beam connected with said bracket, a work-supporting table supported 105 in connection with said table-beam, counterbalancing mechanisms connected with each end of said table, whereby a balanced vertical movement of said table is provided, a work-feeding means carried by said table, 110 and an abrading means supported in connection with said frame above said work-supporting table. 115
15. In a machine of the class described, a work-supporting table, a bracket-member at one end of said table, a driven shaft journaled therein, a feed-belt pulley mounted on said driven shaft, an adjustable bracket-member at the opposite end of said table, a shaft carried thereby, an idler-pulley mounted on said shaft, and a feed-belt running over said feed-belt pulley and said idler-pulley, said adjustable bracket-member com- 120 125

prising a track-piece in which said adjustable bracket-member rides, a series of ratchet teeth connected with said bracket-member, and a pivotally mounted pawl for engaging said ratchet-teeth to hold said adjustable bracket-member in its adjusted position.

In testimony, that I claim the invention set forth above, I have hereunto set my hand this 24th day of November, 1911.

JOHN C. BLEVNEY.
